(57) CLAIM

The ornamental design for a shoe, as shown and described.

DESCRIPTION

FIG. 1 is a top, left, front perspective view of an ornamental design for a shoe;

FIG. 2 is a bottom, left, front perspective view of the shoe of FIG. 1;

FIG. 3 is a front elevational view of the shoe of FIG. 1;

FIG. 4 is a left side elevational view of the shoe of FIG. 1;

FIG. 5 is a right side elevational view of the shoe of FIG. 1; and,

FIG. 6 is a bottom plan view of the shoe of FIG. 1.
The dash-dash-dash broken lines are included for the purpose of illustrating portions of the shoe that form no part of the claimed design.

1 Claim, 6 Drawing Sheets

FIG. 2

FIG. 3

FIG. 4

FIG. 5

FIG. 6
